UNITED STATES PATENT OFFICE.

HARRY A. SHAW, OF CHICAGO, ILLINOIS.

DESIGN FOR A COMB.

57,020.

Specification for Design.

Patented Jan. 25, 1921.

Application filed June 12, 1920. Serial No. 388,649. Term of patent 14 years.

To all whom it may concern:

Be it known that I, HARRY A. SHAW, a citizen of the United States, residing at Chicago, in the county of Cook and the State of Illinois, have invented a new, original, and ornamental Design for Combs, of which the following is a specification, reference being had to the accompanying drawing, forming part thereof.

Fig. 2, is a perspective view of the comb, when seen at a distance.

Fig. 3, is a detail of the end of the comb, and also the socket end of the handle of which the comb is fitted to.

I claim:

The ornamental design for a comb as shown.

HARRY A. SHAW.
